WALL BRACKET FOR A TOWEL BAR OR THE LIKE

Richard S. Latham, Chicago, Ill., assignor to Ekco Products Company, Chicago, Ill., a corporation of Delaware

Filed Aug. 15, 1960, Ser. No. 61,763

Term of patent 14 years

(Cl. D4—3)

Fig. 2

Fig. 1

Fig. 3

Fig. 4

FIG. 1 is a front elevation of a wall bracket for a towel bar or the like, showing my new design.

FIG. 2 is a top plan view thereof.

FIG. 3 is a side elevational view thereof.

FIG. 4 is a sectional view taken substantially along line 4—4 of FIG. 1.

The side of the article opposite that shown in FIG. 3 and the back of the article are substantially plain.

I claim:

The ornamental design for a wall bracket for a towel bar or the like, substantially as shown and described.
